UNITED STATES PATENT OFFICE.

FRANZ LÖSEL, OF BRUNN, CZECHOSLOVAKIA.

BLADING OF FLUID-PRESSURE TURBINES.

Application filed May 16, 1924. Serial No. 713,842.

To all whom it may concern:

Be it known that I, FRANZ LÖSEL, a citizen of Czechoslovakia, residing at Brunn, Czechoslovakia, have invented certain new and useful Improvements in the Blading of Fluid-Pressure Turbines, of which the following is a specification.

My invention relates to the blading of elastic fluid turbines, that is to say of gas or steam turbines. My invention includes the following features, namely the entering edges of the blades particularly in the last rows of the turbine are partly rounded and partly sharp edged, and preferably the entering edges and also if desired the escape edges of the blades are not in the shape of straight radial lines. Preferably that part of each entering edge which is not in the shape of a straight radial line is rounded in transverse section while the remainder of the said edge is sharp edged.

In the annexed drawing:

Fig. 1 is a view in longitudinal section through a part of the rotor and a part of the stator of an elastic fluid turbine, and shows a guide blade row and a rotor blade row in side elevation;

Figs. 2, 3 and 4 are views similar to Fig. 1, but showing, by way of example, other constructional forms of improved blades;

Fig. 5 is a view showing in order from top to bottom sections of the blades shown in Fig. 1 taken on the lines I—I, II—II and III—III, respectively; and

Figs. 6, 7 and 8 are views similar to Fig. 5, but showing sections of the blades in Figs. 2, 3 and 4 respectively.

The stator blades secured in the turbine casing or to the stator carrier z are marked a , a_1 , a_2 and a_3 while the blades mounted in the rotor r are marked b , b_1 , b_2 and b_3 . The direction of the flow of the driving fluid is indicated by the arrow A , d denotes the inner diameter and D the larger outer diameter of the blading.

As is seen in Figs. 1, 2, 3, 4 and the sections therethrough in Figs. 5, 6, 7 and 8, the entering edges of all the constructional forms of my improved blades are partly rounded and partly sharp edged. The entering edges differ from a radial straight line. In the blades a , a_3 and b_3 both the entering edges and the escape edges are curved, in the blades b , a_2 , b_2 the escape

edge is a radial straight line while part of the entering edge is a straight radial line and part thereof is curved. In the blade b_1 , the entering edge and in the blade a_1 both the entering edge and the escape edge are formed by two straight lines at an obtuse angle to each other. It is to be understood that in all cases the edges of the blades are in planes substantially radial to the rotor axis.

The entering edges of the blades and more particularly those parts of the same which are not formed by radial straight lines are rounded in transverse section as shown in the sections Figs. 5-8 while the remaining part of such edges may be sharp as usual. In order to avoid difficulties in mounting and dismounting, the escape edges of the stator blades will, in the majority of cases, be made straight or slightly curved. The spaces between the escape and entering edges of adjacent blades may be of the same width throughout or may vary in width as is seen in Figs. 1 to 4.

This improved blading is more particularly designed for the low pressure end of turbines and especially for their last rows in order to reduce to a minimum the corosions due to moisture and condensed water in the steam or elastic fluid and any injury to the edges of the blades, and in order to prevent the elastic fluid issuing from one blade into the next from blowing and striking against the back of the blades on the entrance side when the load is reduced and the fluid velocities altered and thus by shaping the blades avoid the losses caused thereby and due to eddies, shocks and the like. When the load of a turbine is greatly reduced the velocity of the fluid in the spaces between the blades issuing from one blade into the next is likewise notably reduced and at the same time considerable changes in the directions of flow of the fluid take place as the fluid passes from one row of the blades to the next following one. This resulted more particularly at the low pressure end of the turbine in highly objectionable shocks on the backs of the blades.

The invention offers the advantages that, in shaping the blades according to the invention by rounding partly the entrance edges of the blades or taking off certain parts of the blade edges, by which, in cer-

- tain cases, the entrance edges of the blades differ from a straight line, their entrance angles are altered and the rounded blade edges are more resistant and durable and 5 keep their shape unchanged during all the time of operation. The shaping or rounding of the entrance edges increases by degrees outwardly and radially, as it is evident by the sections shown in Figs. 5, 6, 7 and 8.
- 10 The axial width of the blades may thereby be altered in certain cases as is evident from Figs. 1, 2 and 3, and from their sections Figs. 5, 6 and 7. According to the increased shaping and rounding of the blades outwardly and radially, the entrance edge angle of the blades also increases outwardly and radially, which is made evident by the angles α , α_1 , α_2 ; β , β_1 and β_2 indicated in Fig. 5. This is also evident from Figs. 6, 7 and 8 although the angles are not there indicated. Shaping the blades according to the invention produces the best results and increases the turbine efficiency, reliability and performance, particularly at partial loads and in the low pressure or vacuum end of the turbine.

30 My invention permits such shaping of the blades and their edges that within wide limits of variations of load and the alterations of the fluid velocities and directions due thereto all the working streams of the fluid are taken up by the front working faces of the blades and do not hit or strike their backs, and the blades, particularly at their entrance parts, are subject to wear and tear to a much less extent than heretofore.

40 It is a matter of course that all blades in the low pressure end of a turbine or in a part therein, particularly in the last rows, could be made in one of the shapes described, or in a plurality of shapes within the scope of this invention. But generally only one of the shapes is applied in a turbine.

What I claim is:

- 45 1. A blade for an elastic fluid turbine having an entrance edge partly rounded and partly sharp.
2. In an elastic fluid turbine, a blade row comprising blades, each of which has an entrance edge partly rounded and partly sharp.
- 50 3. In an elastic fluid turbine, a blade row comprising blades, each of which has an entrance edge partly rounded and partly sharp, and a sharp escape edge.
4. In an elastic fluid turbine, a blade row comprising blades, each of which has an entrance edge partly rounded and partly sharp, the rounded part and the sharp part being disposed outwardly and inwardly, respectively, radially of the turbine.
- 55 5. In an elastic fluid turbine, a blade row comprising blades each of which has an entrance edge sharp at one end and changing gradually radially and outwardly of the

turbine into a rounded edge part, having the greatest rounding at the point farthest out along a radial line.

6. In an elastic fluid turbine, at least one rotor blade row comprising rotor blades and 70 at least one guiding blade row, comprising guide blades, each blade of both rows having an entrance edge partly rounded and partly sharp.

7. In an elastic fluid turbine, at least one 75 rotor blade row comprising rotor blades and at least one guiding blade row, comprising guide blades, each blade of both rows having an entrance edge partly rounded and partly sharp, and a sharp escape edge. 80

8. In an elastic fluid turbine, at least one rotor blade row comprising rotor blades and at least one guiding blade row, comprising guide blades, each blade of both rows having an entrance edge partly rounded and 85 partly sharp, the rounded part and the sharp part being disposed outwardly and inwardly, respectively, radially of the turbine.

9. In an elastic fluid turbine, at least one rotor blade row comprising rotor blades and 90 at least one guiding blade row, comprising guide blades, each blade of both rows having an entrance edge sharp at one end and changing gradually radially and outwardly 95 of the turbine into a rounded edge part, having its greatest rounding at the point farthest out along a radial line.

10. A blade for an elastic fluid turbine having an entrance edge partly rounded and partly sharp, and formed so that the entrance edge angle increases towards the end of the blade which is outward with respect to the turbine. 100

11. In an elastic fluid turbine, a blade row 105 comprising blades, each of which has an entrance edge partly rounded and partly sharp, and changing gradually from the sharp portion to the rounded portion, so that the entrance edge angle increases gradually with the increased rounding.

12. In a fluid pressure turbine having a stator and a rotor, a blade having an entrance edge, at least part of which is rounded in transverse section and which differs at least in part from a straight line radial to 115 the axis of said rotor.

13. In a fluid pressure turbine having a stator and a rotor, a blade having an entrance edge including a portion partly rounded in transverse section and a sharp remaining portion, said entrance edge differing at least in part along such curved edge section from a straight line radial to the rotor axis. 120

14. In a fluid pressure turbine, a stator, a 125 rotor, and blading including blades at the low pressure end of the turbine, each of such blades having an entrance edge, at least part of which is rounded in transverse section and which differs at least in part from a 130

straight line radial to the axis of said rotor.

15. In a fluid pressure turbine, a stator, a rotor, and blading including blades at the low pressure end of the turbine, each of such blades having an entrance edge, at least part of which is rounded in transverse section and the remaining portion is sharp.

In testimony whereof I affix my signature in presence of two witnesses.

FRANZ LÖSEL.
